UNITED STATES PATENT OFFICE.

ABRAHAM GRÖNVOLD WESTAD AND ERIK LUDVIG HÄGG, OF HUNSFOS, NORWAY.

CIRCULATING APPARATUS FOR CELLULOSE DIGESTERS.

1,309,267.

Specification of Letters Patent.

Patented July 8, 1919.

Application filed March 8, 1919. Serial No. 281,502.

To all whom it may concern:

Be it known that we, ABRAHAM GRÖNVOLD WESTAD, engineer, and ERIK LUDVIG HÄGG, workmaster, citizens of Norway, residing at Hunsfos, Norway, have invented certain new and useful Improvements in Circulating Apparatus for Cellulose Digesters, of which the following is a specification.

10. The digesting of cellulose commonly takes place by direct or indirect steam supply. When the steam is directly supplied to the digester or to the lye in the manner hitherto practised, the lye at the bottom of the digester will always be weaker (thinner) than in the top of the apparatus, because the lye does not circulate in the proper way. It will stream upward in the central part of the digester and downward along the sides of the same at a proportional slow rate. The result is, that the preparation of the mass will be faster finished in the upper part of the digester than in the lower, which also involves a prolonged digesting time and a heterogeneous product. When the digesting is performed indirectly by means of tube coils, etc., inside of the digester, this drawback is avoided, because the circulation takes place at a faster rate, as the lye streams upward along the sides of the digester, and downward in the central part. The indirect digesting implies however the employment of steam tube coils inside of the digester, which coils very soon will get a covering, which highly decreases the heat transmission, and therefore must be removed at short intervals of time.

The present invention has for its object a circulating apparatus, at which the advantages of the indirect digesting are obtained by use of direct steam supply.

The invention is shown in the accompanying drawing which shows a length section through a digester comprising the new circulating apparatus.

The lower part of the digester is formed like a cylinder —1— with bottom lid —2— and with one or more steam inlets —3—. Into this cylinder the circulating apparatus is inserted. This is formed as a hollow cylinder —4— of somewhat lesser diameter than the cylinder —1—, whereby an annular compartment —5—, is formed into which the steam is let in.

45. The inner cylinder —4— has on its outer

side some ribs —6—, which are bent into the shape of a screw thread and will impart a fast rotating movement to the steam before it enters the lower, openings —7— of a set (row) of tubes —8— which are facing the direction of the rotation and are arranged on the outside of the upper part of the cylinder —4—, lead upward into the digester and here are directed aslant outward along the inner conical wall of the digester. 65 The cylinder —4— terminates on its top in a strainer —9—.

When the steam is let into the digester through the tubes —8—, it has the direction of the arrows. It is forced outward toward the outer wall of the digester and upward along this wall, whereby the lye is driven into the same direction, thus being forced to stream downward in the central part, through the strainer —9—, into the interior of the cylinder, down to the bottom —2—, out through the side openings —10— in the cylinder —4—, whereupon it again is forced by the inflowing steam and rotating will ascend into the intermediate compartment —5—.

In this way a lively and effective circulation of the lye is obtained during the entire time of digesting as also an intimate interconnection between the steam and the lye, a 35 homogeneous product and a shorter time of digesting. It is also possible to work at a lower digesting temperature than customary.

Claims:

1. In a circulating apparatus for cellulose digesters, a body having a cylindrical lower portion provided with steam inlets a closure for said lower portion, a cylinder in the lower portion of the body providing a steam compartment and having openings at its lower end, a strainer at the upper end of the cylinder and means for directing the course of the steam and lye supplied to the body to insure of a continuous circulation of 95 the lye and steam upwardly along the walls of the body and downwardly through the center thereof and through the cylinder.

2. A device as claimed in claim 1 wherein the means includes tubes arranged between the cylinder and lower cylindrical portion of the digester body.

3. A device as claimed in claim 1 where in the means comprises spiral ribs on the outer surface of the cylinder and within the 110

steam compartment and angularly bent tubes between the cylinder and the upper edge of the cylindrical portion of the body.

4. In an apparatus of the character described, a digester body having a cylindrical lower portion provided with steam inlets, a closure for said lower portion, a cylinder arranged in the cylindrical lower portion and spaced from the inner surface thereof to provide an annular steam compartment, said cylinder having openings at the lower end and having the upper end enlarged, a strainer covering the upper end of the cylinder, spiral ribs on the outer surface of the cylinder and in the steam compartment, and

a plurality of tubes arranged between the cylinder and the lower portion of the body having their lower portions open and facing the direction of passages of the steam in the compartment and having their upper ends bent angularly and projecting into the main portion of the body of the digester. 20

In testimony whereof we affix our signatures in the presence of two witnesses.

ABRAHAM GRØNVOLD WESTAD.
ERIK LUDVIG HÅGG.
